[57] CLAIM

The ornamental design for a chest, as shown and described.

DESCRIPTION

FIG. 1 is a front perspective view of a chest showing my new design;

FIG. 2 is a modified embodiment of the chest shown in FIG. 1, the opposite side being a mirror image thereof and the rear being similar to that of FIG. 1 but taller; FIG. 3 is a front elevational view of FIG. 1;

FIG. 4 is a top plan view thereof;

FIG. 5 is a side elevational view thereof, the opposite side being identical thereto; and

FIG. 6 is a rear elevational view of FIG. 1.
